UNITED STATES PATENT OFFICE

2,164,824

HOPPER

George Kohlhardt, Wauwatosa, Wis.

Application June 17, 1937, Serial No. 148,810

1 Claim. (Cl. 221—118)

My invention relates to hoppers, and more particularly to a type of hopper that acts as a reservoir supply chamber for material to be fed by gravity to an outlet at the bottom.

5 The object of my invention is to provide a means of preventing materials such as coal from arching across the bottom outlet, when used in stokers or the like.

Another object of my invention is to provide 10 a means of permitting air to circulate around the materials so as to provide an even temperature to the material, thus preventing one side of the hopper to feed faster than the remaining portion.

15 It is manifest to anyone familiar with the feed hoppers, such as are used in fuel stokers for heating plants, or the like, that the uneven shape of the fuel often causes an arch to be developed in which the material, due to gravity, causes the 20 center portion to create a pressure on the outer portion causing it to force against the sides of the hopper, and preventing a steady feed to the bottom opening, in which case there is a lack of fuel supply causing an inconvenience as well 25 as a hazard.

The construction of my device is such that owing to its invert conical design, the weight 30 of the fuel or the like presses the fuel down causing a release in the pressure against the sides 35 of the hopper.

The device is constructed in the form of an inner shell spaced and supported inwardly from the outer shell to provide an air space between the inner and outer shell and permitting the circulation of air thereby causing an even temperature 40 around the entire inner hopper shell supporting the fuel.

The invention consists of the following features exemplified in the accompanying drawing 45 in which

Fig. 1 is a fragmentary cross sectional view of the device as applied to a conventional type of stoker, illustrating the manner in which the inner invert conical hopper is suspended within 50 the enclosure formed by the outer hopper.

Fig. 2 is a top view of the inner and outer hopper arrangement, and

Fig. 3 is a perspective view of an inner hopper constructed for a cylindrical shaped unit.

55 Similar characters of reference indicate corresponding parts throughout the several views, and referring now to the same, the character 10 represents an outer shell of cylindrical design such as is used as a conventional type of stoker hop-

per arranged to feed fuel to a screw type conveyor 11 or the like, that will transfer the fuel to the fire box. The conveyor 11 is shown driven by a motor 12 attached to the conveyor shaft by means of a coupling 13. The top of the hopper 10 is provided with an extension 14 having a cover 15 hinged at 16 to its wall. Inside of the hopper shell 10 is shown an inner shell 17 suspended from the outer shell 10 by means of spacers 18 and 18' permitting air circulation at 19. The spacers 18 are longer than the spacers 18' due to the cone shaped construction of the inner shell 17 which is smaller at the upper edge 20 than the diameter of the lower edge 21. Bolts 22 are shown as supporting the spacers 15 18 and 18'.

In operation the inner shell 17 supports the fuel acting as a hopper to supply the conveyor 11. The air spacer 19 between the inner shell 17 and the outer shell 10 permits the fuel inside the inner shell 17 to maintain an even temperature thus causing an equal feed of the fuel which slides down toward the conveyor 11 by gravity and the walls of the shell 17, being tapered larger at the bottom, provide easier sliding action and relieve the frictional resistance between the fuel and the hopper sides.

The device is shown as cylindrical in structure but any desired shape may be employed, as the principle adapts itself equally as well to a rectangular or any other shape or hopper.

In the chosen embodiments of my invention there are present several new and useful features not heretofore shown in the prior art, but the right is herein reserved to make such changes 35 as are found necessary without departing from the spirit of the invention as set forth in the appended claim.

Having thus described my invention, what I claim and desire to secure by Letters Patent in 40 the United States, is:

The combination with an outer shell of an inner hopper shell, said inner shell being of conical construction having its lower edge greater in diameter than its upper edge, spacers attached 45 to said inner shell, said spacers disposed for suspending said inner shell from said outer shell permitting air circulation between said inner and outer hopper shell, said outer shell terminating into a hopper at its lower end to receive material dispensed by gravity from said inner hopper shell.

GEORGE KOHLHARDT.
